Primary Examiner—A. Hugo Word*Assistant Examiner*—Cathy Anne MacCormac*Attorney, Agent, or Firm*—Heslin & Rothenberg**[57]****CLAIM**

The ornamental design for a treadle actuated pet dish or similar article, as shown and described.

DESCRIPTION

FIG. 1 is a front elevational view of a treadle actuated pet dish or similar article showing my new design;
 FIG. 2 is a rear elevational view thereof;
 FIG. 3 is a right side elevational view thereof, the opposite side being a mirror image of the side shown;
 FIG. 4 is a top plan view thereof;
 FIG. 5 is a bottom plan view thereof;
 FIG. 6 is a top plan view of a treadle actuated pet dish or similar article with the treadle depressed and cover raised; and
 FIG. 7 is a right side elevational view of FIG. 6.
